UNITED STATES PATENT OFFICE.

CHARLES H. HILL, OF SCRANTON, PENNSYLVANIA.

UMBRELLA.

No. 885,752.

Specification of Letters Patent. Patented April 28, 1908.

Application filed October 15, 1906. Serial No. 338,894.

To all whom it may concern:

Be it known that I, CHARLES H. HILL, a citizen of the United States, residing at Scranton, in the county of Lackawanna and State of Pennsylvania, have invented certain new and useful Improvements in Umbrellas, of which the following is a specification.

My invention relates to improvements in ribs and stretchers for umbrellas and pertains more particularly to the securement of the same in such a manner as to render them individually removable and replaceable.

Reference is to be had to the accompanying drawings in which similar characters of reference denote corresponding parts in all the figures.

Figure 1 is a side elevation of the umbrella partly broken away, and embodying my improvements. Fig. 2 is an end view of the notch. Fig. 3 is a central vertical sectional view of the same. Fig. 4 is a view of the ring employed in the end of the notch 3. Fig. 5 is a top plan view of the upper end of the runner. Fig. 6 is a central vertical sectional view of the same. Fig. 7 is a top plan view of a part of one of the ribs or stretchers showing a tip applied thereto. Fig. 8 is a side elevation of Fig. 7. Fig. 9 is a detached view of one of the tips. Fig. 10 is an under plan view of a modification. Fig. 11 is a top plan view of the same. Fig. 12 is a side elevation of Fig. 11. Fig. 13 is an elevation of a modified tip. Fig. 14 is a vertical section of Fig. 11. Fig. 15, is a view in perspective of Fig. 10, showing parts 11' but partially bent into position.

The umbrella comprises the ordinary stick, provided with a notch 2 which is formed with an enlarged base 3, a shoulder or seat 4, and with a plurality of integral bendable fingers 5, which are separated by notches or cuts 6, which latter are of sufficient width to readily permit of the insertion and removal as well as movement of the rib tips shortly to be referred to. A ring, 7, seats on shoulder 4 and is confined thereto by bending fingers 5 over into close engagement therewith, the end extremities of the fingers abutting shoulders 4.

The body of each rib and stretcher 8 and 9 respectively, is of ordinary material and 50 U-shaped in cross section. Each, of these, however, is fitted with a brass hooked-tip 10, which is received in the U-shaped portion of the ribs and stretcher and which is formed with depressions 11 on its lower longitudinal edge, adapted to receive swaged portions of the metal as at 11' at the two longitudinal

side portions of the said U-shaped body, the latter being squeezed at its end to closely embrace the tip, as shown in Fig. 10. As a modification of this method the tip may be fastened in the main body by rivets 14, extending transversely through the tip and rib, which rivets are subsequently headed at their ends. As a still further modification the tips may have protuberant points 12 on their upper longitudinal edges adapted to fit and be riveted in holes provided therefor in the base of the U-shaped bodies.

The tips on their top longitudinal edges are each formed with right angular shoulders 10' against which the end e, of the ribs abut. Thus in assembling the parts shoulders 10' are brought to engage the ends e, of the ribs, which thereby assures that the hooks of the tips will project the proper distance beyond the ends e, of the ribs. The hooks are formed with eyes d, oblique face b, and bendable bills c, the latter having an oblique face which contacts with face b. This oblique disposition of the faces of said parts enable 80 the hooks to be easily positioned and removed and provides a joint between the bill and face b, which is proof against accidental separation.

The hooks of the tips are adapted to be 85 passed over the rings in the notches on the notch and runner and over the pintle 15, which is appended from each rib by two ears as in ordinary constructions. Such engagement is made permanent by compressing the 90 point of the hook into close engagement with its body. Thus removal of ribs is made easy by the insertion of any edged instrument between said point and body by prying same to sufficient width for the passage of 95 the ring or pintle. The construction of the slide runner is precisely similar to that of the crown notch, the sole distinction residing in the fact that the body of the former is of greater length than that of the latter.

Among the many advantages appertaining to my invention, not the least, resides in the practically rust proof tips and ring which will materially lengthen the life of an umbrella, the weakest construction of which is 100 inevitably at such a delicate point. Another great advantage is the possibility of individual removal and insertion. This is so plainly and incalculably superior to the old wire-stringing method that it need not be dilated 110 upon except for the statement that the loosening or breaking of one tip or rib, in the

wire-method, necessitates the difficult work of restringing or rewiring the entire number of ribs.

Having thus described my invention what I claim as new and desire to secure by Letters Patent is—

1. In combination with an umbrella rib of U-shape in cross section, a tip having its top longitudinal edge formed with a shoulder adapted to abut against the outer end of said rib, means to secure the tip to said rib, said tip beyond said shoulder thereof being formed with a hook having an oblique face, the bill of said hook having a long oblique face to engage said first named face, the end of said hook being disposed on the under longitudinal edge of said tip.

2. In combination with an umbrella rib of U-shape in cross section, a tip therefor having a hooked end, said tip being of such thickness to be received between the legs of the U and being formed on its under face with a pair of spaced depressions, each of the free longitudinal edges of the legs of the U at points clinching with said depressions, being bent inwardly towards one another to occupy the space formed by said depressions and be-

ing disposed at right angles to the side faces of said tip.

3. In an umbrella, a runner having a ring 30 and a series of spaced fingers to secure said ring in position, tips engaging in said space between said fingers and each having hook-shaped ends and an eye at the inner end of said hook, said hook on its under side being 35 formed with an oblique face which extends from said eye to the hook extremity, the under side of said tip having an oblique face which extends from said eye rearwardly and which is to engage said oblique face of the 40 hook, said hook being comparatively long so that when its eye is positioned with respect to said ring, the hook extremity will be at a point away from said fingers which secure said ring, and means carried by the tip to engage the outer end of the rib to thereby properly position said hook with respect to the outer end of the rib.

In testimony whereof I affix my signature in presence of two witnesses.

CHARLES H. HILL.
